US00D631467S

(12) **United States Design Patent**
Shimizu et al.

(10) **Patent No.:** US D631,467 S
(45) **Date of Patent:** ** Jan. 25, 2011

(54) **COVER FOR CONNECTING TERMINAL OF ELECTRONIC DEVICE**

(75) Inventors: **Yosuke Shimizu**, Tokyo (JP); **Masaaki Ohara**, Tokyo (JP)

(73) Assignee: **Sony Corporation**, Tokyo (JP)

(**) Term: **14 Years**

(21) Appl. No.: **29/347,899**

(22) Filed: **Jul. 19, 2010**

Related U.S. Application Data

(63) Continuation of application No. 29/347,140, filed on Sep. 30, 2009, now Pat. No. Des. 624,052.

(30) **Foreign Application Priority Data**

Apr. 10, 2009 (JP) 2009-008312

(57) **CLAIM**

The ornamental design for a cover for connecting terminal of electronic device, as shown and described.

DESCRIPTION

FIG. 1 is a front, top, right perspective view of a cover for connecting terminal of electronic device showing our new design;

FIG. 2 is a rear, top, left perspective view thereof;

FIG. 3 is a rear, right, bottom perspective view thereof;

FIG. 4 is a front, left, bottom perspective view thereof;

FIG. 5 is a top plan view thereof; and,

FIG. 6 is a bottom plan view thereof.

The broken lines illustrate unclaimed portions of the cover for connecting terminal of electronic device and form no part of the claimed design.

1 Claim, 6 Drawing Sheets
